DESIGN FOR A PACK FOR GLASS TUMBLERS
OR LIKE FRAGILE ARTICLES

Ernest L. Shepard, Fairfield, Maine, assignor, by
mesne assignments, to The Canal National
Bank of Portland, Portland, Maine, a national
banking association, and William B. Nulty,
Portland, Maine, as trustees

Application February 23, 1946, Serial No. 126,859

Term of patent 14 years

(Cl. D58—13)

To all whom it may concern:

Be it known that I, Ernest L. Shepard, a citizen
of the United States, residing at Fairfield, in the
county of Somerset, State of Maine, have invented
a new, original, and ornamental Design for Pack
for Glass Tumblers or Like Fragile Articles, of
which the following is a specification, reference
being had to the accompanying drawing, forming
part thereof.

Fig. 1 is a top perspective view of a pack for
glass tumblers or like fragile articles showing my
new design, the pack being shown in open position.

Fig. 2 is a bottom perspective view thereof, and
Fig. 3 is an end view of such pack, closed.

I claim:

The ornamental design for a pack for glass
tumblers or like fragile articles, as shown.

ERNEST L. SHEPARD.
